UNITED STATES PATENT OFFICE.

FREDERICK W. STORCK, OF SOMERVILLE, MASSACHUSETTS.

DIAPHRAGM-HORN.

1,186,615.

Specification of Letters Patent. Patented June 13, 1916.

Application filed December 17, 1915. Serial No. 67,462.

To all whom it may concern:

Be it known that I, FREDERICK W. STORCK, a citizen of the United States, residing at Somerville, in the county of Middlesex and 5 Commonwealth of Massachusetts, have invented certain new and useful Improvements in Diaphragm-Horns, of which the following is a specification.

My invention relates to a device which is 10 particularly useful as an automobile horn or a horn for motor boats. It is essentially a device of a well-known type wherein the sound is produced by a roughened or toothed wheel revolving in contact with a member 15 borne by a diaphragm and it has been the special object of my invention to construct a device which is capable of easy adjustment so as to produce sounds of varying quality, duration and intensity and to compensate 20 for the wear of certain parts.

It has been my further object to so design and construct my device that it will be simple and easy to manufacture and to operate and readily mounted in convenient positions 25 for operation.

My device may be best understood by reference to the accompanying drawings in which—

Figure 1 is a horizontal cross-section. 30 Fig. 2 is a top view with the casing and diaphragm shown in cross-section. Fig. 3 is a cross-section on line 3—3 of Fig. 2. Fig. 4 is a cross-section on line 4—4 of Fig. 1, and Fig. 5 is a cross-section on line 5—5 of Fig. 1.

Referring now more specifically to the drawings, in which like reference figures indicate like parts, 1 is a metal casing containing the moving parts, which casing is 40 provided with an annular flange 2. The horn 3 has an annular base extension 4, also provided with a flange 5 which lies opposite and overlaps flange 2. These flanges 2 and 5 embrace the edge of diaphragm 6 which is made of thin, flexible steel, and hold the diaphragm tightly in place with the assistance of bolts 7 and nuts 8 which pass through holes in the flanges and diaphragm. The diaphragm 6 has 50 washers 9 on each side thereof, preferably made of paper, fabric or rubber which separate it from the flanges 2 and 5 and serve to assist in holding it tightly in place. In a hole in the center of diaphragm 6 is firmly 55 fixed a hard metallic contact member 10 provided with a thin extension 11.

The casing 1 is punched inwardly to form four shoulders 12 (see Fig. 5) which form slideways for a frame 13 which is thereby 60 slidably mounted in the casing against which it bears firmly by spring tension. The sliding movement of frame 13 is controlled by the screw 14 the threaded end of which passes through a threaded hole in the central rear portion of the frame. This screw 65 14 is provided with a flange 15 against which the spring washer 16 presses firmly, and, as the screw passes through a hole in the central rear portion of the casing 1 and is provided on its outer end with a collar 17 fastened thereon by means of a pin 18, the 70 spring-washer 16 will cause the collar 17 to be firmly pressed against the outside of casing 1, thereby holding the screw firmly in position.

Between the sides of the frame 13 is non-rotatably mounted a spindle 19 on which is loosely mounted and free to revolve a fly-wheel 20 which butts against the enlarged end 21 of the spindle 19. (See Fig. 4.) 80 This fly-wheel 20 has attached thereto by means of rivets 22 a toothed wheel 23 which is held in spaced relation therewith by means of the washers 24. The wheel 23 has a round hole 25 in its center through which a pinion 26 freely passes and butts at one end against the fly-wheel 20 and at its other end against the idle roller 27 which has a flange 28. A collar 29, fast on the spindle 19, holds the parts borne by spindle 19 in close relation, and the spring washer 30 borne by the spindle tends to press the sides of frame 13 apart, thus causing them to get a firm frictional bearing against casing 1, the end of spindle 19 adjacent to the spring 95 washer 30 fitting loosely in a hole in bracket 13 to permit this.

Loosely mounted on a rivet 22 between fly-wheel 20 and toothed wheel 23 is a pawl 31 which engages the pinion 26 and prevents its independent movement in one direction as it is constantly held in engagement with the pinion by means of spring 32, one end of which is laterally extended and anchored in a slot 33 in wheel 23 so as to give the spring a firm bearing against a rivet 22 on one side and the back of the pawl 31 on the other side, as shown in Fig. 3, where it is apparent that the pawl 31, because of the shape of its tooth 34, will rise against the tension of spring 32 and permit the free and independent rotation of the pinion 26 in one direction.

tion, whereas if the pinion is rotated in the other direction it will remain locked with the pawl and cause the fly-wheel 20, which bears the pawl and its attached toothed wheel 23, to be rotated with it. This rotation of the various rotatable parts is effected by the rack-bar 35 which is provided with a handle or pusher 36 and which has a serrated edge 37 for engaging the pinion 26. 5 This bar 35 is rectangular in cross-section and enters casing 1 through a rectangular slot which is formed by punching out the metal in a manner whereby three edges are cut away so that the punched out portion is 10 turned down, thereby forming a lug or shoulder 38 as a bearing. A coil spring 39 is attached at one end to a slot 40 in the inner end of the rack bar and at its other end to a hole 41 in a lug 42 punched out of the 15 top of casing 1, the hole thereby formed being covered by plate 43. This spring 39 holds the rack-bar in engagement with the pinion 26, and returns it to its normal elevated position while at the same time permitting its free movement. The rack-bar 20 35 has a slot 44 adjacent to its serrated portion whereby it embraces the flange 28 on the idle roller 27. As the rim of flange 28 contacts with the bottom of slot 44 it serves 25 to hold the rack-bar and pinion in proper spaced relation so as to keep their teeth from "bottoming," as it will be readily seen from the foregoing that the rack-bar 35 is swingable so as to be kept in operative 30 engagement with the pinion 26 whatever the position of adjustment of the wheel 23 in respect to the diaphragm 6.

Thus it will be seen that the flange 28 serves to retain the rack-bar 35 in proper 40 alignment whether pressure of the operator's hand is directly and evenly applied thereon or not.

As the toothed or serrated edge of the wheel 23 contacts normally with the edge of 45 the extension 11, or the contact member 10 borne by the diaphragm 6, it will be apparent that the device will produce sound upon the revolution of the wheel 23 by means of the downward thrust of the rack-bar 35 50 which will revolve the pinion 26 and fly-wheel 22 which is locked therewith by the pawl 31 in this direction of forced rotation. When the downward movement of the rack-bar ceases or the bar is returned to normal 55 position by spring 39 the pawl will permit the continued rotation of the fly-wheel 22 and the toothed wheel 23.

For mounting my horn upon the side of an automobile or deck of a boat or other 60 place where its use may be desired I have provided an adjustable bracket 45 with upwardly extending arms 46 and 47, arm 46 being provided with a small hole so that it may be clamped in place against flange 2 65 by means of a bolt 7 and nut 8. The arm 47

is provided with a large hole so that it may embrace the collar 17 and it is made with sufficient spring tension so that it will readily maintain itself in place. Holes may be made in the base of the bracket so that it 70 may be held in position by screws passing through said holes, or it may be otherwise clamped or retained in position. The angle of adjustment of the bracket in relation to the rest of my device may be varied by 75 clamping arm 46 by different bolts 7 in turn, there being preferably six or seven of these bolts used to retain flanges 2 and 5.

From the foregoing it will be apparent 80 that my horn will be free from objectionable rattling because its parts are held firmly together by spring tension notwithstanding the fact that they are capable of free movement and adjustment, which adjustment is easily obtained because of the accessibility 85 of the adjusting screw 14. If this screw is set up so as to force the wheel 23 into close relation with part 11 of the contact member 10 a short, sharp high pitched tone will result, whereas a lower and more prolonged 90 tone will be caused if the wheel 23 is slightly withdrawn as the fly-wheel is of sufficient weight to gather momentum as it spins so that its rotation will be maintained for some time after the initial operating force has ceased. Thus, the horn may be quickly and easily adjusted to the varying requirements 95 of traffic, and the wear of the contacting sound-producing parts may be compensated.

Although I have employed in the particular form of my device herein described a wheel 23 having a notched, or toothed, periphery for striking the contact member 10, it is not to be understood that I limit my invention to this form of roughened wheel as 100 a wheel having separate projecting members attached thereto, on its periphery, or elsewhere, if the wheel is disposed at a different angle to the diaphragm, may equally well be used.

It will also be readily understood that the frame 13 may be constructed with sufficient spring tension of its own to make spring washer 30 unnecessary, yet I prefer to use 110 the spring washer notwithstanding the fact that I prefer to construct the frame with some spring tension of its own whereby it may be brought to bear in frictional engagement with its slideways.

Having thus fully described my invention 115 what I claim is:

1. In a device of the character specified the combination of a casing, a diaphragm, a contact member mounted on said diaphragm, a wheel arranged to strike said contact member and an expansible slidable frame whereon said wheel is mounted, said frame being adapted to bear with firm spring-tension against said case.
2. In a device of the character specified 120

- the combination of a casing, a diaphragm, a contact member mounted on said diaphragm, a roughened wheel, arranged to strike said contact member, an expansible frame where-
 5 on said wheel is mounted, slideways in said casing whereby said frame is movably supported, a spring arranged to press the sides of said frame into firm frictional engagement with said slideways and means for
 10 moving said frame and adjustably fixing the relation of said wheel to said contact member.
3. In a device of the character specified the combination of a casing, a frame slid-
 15 ably mounted in said casing and provided with a threaded hole, a screw passing through said casing and entering said threaded hole, a collar fast on said screw on the part thereof outside said casing, said
 20 screw being provided with a flange on the part thereof inside said casing and a spring washer arranged to press against said flange and hold said screw in position by forcing said collar against said casing.
- 25 4. In a device of the character specified a casing, a frame slidably mounted therein, a spindle borne by said frame, a roughened wheel on said spindle, a pinion on said spindle, a pawl attached to said wheel, a spring arranged to hold said pawl in yielding contact with said pinion, said pawl being ar-
 30 ranged to lock with said pinion in one direction of its rotation only, a rack-bar ex-
 35 tending through an aperture in said casing and meshing with said pinion and a spring for holding said rack-bar in operative engagement with said pinion.
5. In a device of the character specified a casing, a frame slidably mounted therein, a spindle borne by said frame, a roughened wheel on said spindle, a pinion on said spindle, a pawl attached to said wheel, a spring
 40 arranged to hold said pawl in yielding contact with said pinion, said pawl being ar-
 45 ranged to lock with said pinion in one di-
 50 rection of its rotation only, a slidable and swingable rack-bar extending through an aperture in said casing and meshing with said pinion, and a spring for holding said rack-bar in operative engagement with said pinion.
6. In a device of the character specified a casing, a frame slidably mounted therein, a spindle borne by said frame, a roughened wheel on said spindle, a pinion on said spindle, a pawl attached to said wheel, a spring arranged to hold said pawl in yielding contact with said pinion, said pawl being ar-
 55 ranged to lock with said pinion in one di-
 60 rection of its rotation only, an idle roller provided with a flange adjacent to said pinion, a rack-bar extending through an aperture in said casing and meshing with said pinion, said rack-bar being provided with a slot forming a bearing for said flange, and a
 65 spring for holding said rack-bar in oper-
 ative position.
7. In a device of the character specified the combination of a casing provided with an annular flange, a member protruding from the central back portion of said casing, a plurality of bolts extending through said flange, a bracket having one upwardly ex-
 70 tendsing arm, which arm is provided with a hole whereby it may embrace said member
 75 protruding from the central back portion of said casing, and another arm provided with a hole whereby it may be secured to said flange by any one of the bolts passing through said flange.

80 In witness whereof I hereunto affix my signature.

FREDERICK W. STORCK.
